RADIATOR CONSTRUCTION

Filed April 7, 1924

Inventor:
Frank A. Merrill
by *Heard Smith & Tennant.*
Atty.

UNITED STATES PATENT OFFICE.

FRANK A. MERRILL, OF MALDEN, MASSACHUSETTS.

RADIATOR CONSTRUCTION.

Application filed April 7, 1924. Serial No. 704,630.

To all whom it may concern:

Be it known that I, FRANK A. MERRILL, a citizen of the United States, and a resident of Malden, county of Middlesex, State of Massachusetts, have invented an Improvement in Radiator Constructions, of which the following description, in connection with the accompanying drawing, is a specification, like characters on the drawing representing like parts.

This invention relates to improvements in radiators and the general object thereof is to provide a radiator construction comprising a heating section and a conduit integral with said heating section having at its ends means for connecting the conduit into a riser of the heating system thereby avoiding the necessity of the usual piping and elbows required to connect the riser to the radiator.

By the present invention the radiators can be more readily assembled in the heating system, the sizes and types of fitting simplified, and the cost of construction and installation greatly reduced.

A further object of the invention is to provide a novel radiator section which can be assembled with standard radiator sections for the purpose above stated.

A further object of the invention is to provide radiator sections which may be employed either in a one pipe steam system, in which the steam and water of condensation may be introduced and delivered through the same valve, or a radiator section which will permit the introduction of the heating fluid at the top and the discharge thereof at the bottom, or radiator sections which may be employed in a two pipe system in which the heating fluid is introduced into one section and delivered from another through conduits integral with the respective sections adapted to be connected into and form parts of the supply and return risers respectively.

A further object of the invention is to provide radiator sections of the character above described in which any suitable type of valve, either manually or automatically operable, may be employed.

Other objects and features of the invention will more fully appear from the following description and the accompanying drawing and will be particularly pointed out in the claims.

A preferred embodiment of the invention

is illustrated in the accompanying drawing, in which,

Fig. 1 is an elevation of a radiator embodying the invention as applied to a two pipe system for the heating fluid;

Fig. 2 is a vertical longitudinal sectional view of a preferred form of radiator section embodying the invention adapted to be used either in a one pipe or two pipe system; and,

Fig. 3 is a vertical longitudinal sectional view of another type of radiator section having a thermostatically operated valve for controlling the discharge of the heating fluid into the return riser of the heating system.

The invention as illustrated in Fig. 1 comprises a radiator 1 having end sections 2 and intermediate sections 3 which may be of a standard type and also having an intake section 4 and an outlet section 5 embodying a preferred form of the invention. The intake section 4, which is illustrated in vertical section in Fig. 2, comprises a heat radiating section or loop 6 of any desirable length having in its sides upper and lower nipples 7 and 8 to communicate with other juxtaposed sections of the radiator which may be and preferably are of a standard type. The intake section 4 is provided with an integral conduit 9 which extends longitudinally of the heat radiating section 6 and portions 10 and 11 of the wall of which preferably are common to both the heat radiating section and the conduit. Desirably a space 12 is provided intermediate of the sections 10 and 11 to permit circulation of air through the radiator. The conduit 9 desirably is upon the back side of the radiator and the projection from the rear face of the radiator thereby rendered inconspicuous.

The opposite ends of the conduit 9 are provided with coupling means by which the conduit may be connected directly into a riser for the heating fluid to form a continuous part of the riser.

By reason of this construction the usual piping and elbows, required to connect the radiator to the riser, are eliminated as the conduit 9 forms a direct part of the riser itself.

As illustrated the upper end portion of the conduit 9 is provided with an externally screw threaded boss 13 which is con-

- nected by an expansion joint 14, such as a corrugated copper joint, to the section 15 of a supply riser leading to an upper story in the building in which the radiator is installed, while the lower end of the conduit 9 is provided with an internally screw threaded boss 16 which receives and is coupled to the upper end of a lower section 17 of the supply riser for the heating fluid.
- 10 The heating section of the radiator is provided with an extension 18, the wall of which is integral with that of the conduit 9 and a suitable port 19 in this integral wall provides a passage for the heating fluid into the heat radiating section.
- Any suitable manually operated or automatically operated valve may be provided to control the flow of heating fluid from the conduit 9 into the heating section 6. As 20 illustrated a member 20, forming a valve seat, is screwed into the wall of the aperture and is provided with two or more diametrically disposed sectors 21 with corresponding apertures therebetween. The stem 22 of a suitable valve 23, having sectors corresponding to the sectors of the valve seat, is rotatably mounted in or upon the central portion of the valve seat and the valve is held seated by a helical spring 24 surrounding the valve stem and abutting at one end against the valve stem and at its other end upon a flanged head 25 which is screwed into a suitable opening in the front of the extension 18 of the radiator section. The valve stem 22 is suitably bushed and is provided with an actuating handle 26 by means of which the valve opening may be controlled.
- In the present construction the heating 40 fluid from the conduit 9, therefore, enters the heating section 6 through the regulating valve and thence passes through the nipples 7 of the other radiator sections and returns through the lower nipples 8 to a section having suitable means for delivering the spent heating fluid to a return riser of the heating system.
- A preferred form of outlet section 5 is 50 illustrated in Fig. 3 and comprises a heat radiating section 27 preferably corresponding in form to the adjacent standard radiator units and having an integral conduit 28 extending longitudinally thereof, the end sections of the conduit having common walls 29 and 30 with the heat radiating unit, with an intermediate space 31 between the walls of the heating section and the conduit to permit the circulation of air. The conduit 28 desirably is at the rear of the 60 heating section and is straight and adapted to be connected into and form a part of the return riser. The ends of the conduit are provided with means for connecting the conduit directly into the riser to form a part thereof.

As illustrated the upper end of the conduit 28 is provided with an internally screw threaded boss 32 which is connected to an upwardly extending section 33 of the return riser. The lower end of the conduit is provided with an externally screw threaded boss 34 adapted to be coupled to the downwardly extending section 35 of the return riser.

The heating section 27 is provided with a downward extension 36 having an opening at its front to receive a screw threaded flanged cap 37 which forms a seat for a valve which preferably is operated by a bellows 38 containing an expansible fluid. A valve 39 secured to the bellows is positioned to engage a valve seat 40 having a screw threaded exterior portion which engages complementary screw threads in an aperture in the common wall 30 of the conduit and heating section.

In the operation of the radiator illustrated in Fig. 1 the heating fluid enters through the riser 17 and conduit 9 which forms a part thereof, thence passes through the valve-controlled opening in the upper portion of the intake section into the heat radiating section 6, from which it passes through the nipples 7 progressively through the radiator sections and returns through the nipples 8 of the radiator sections to the outlet section 5, from which it passes into the extension 36 and the condensate accumulates around the thermostatic bellows 38 of the valve 39, thereby cooling the expansible fluid contents of the bellows and causing the bellows to contract and remove the valve 39 from its seat, thus permitting the condensate to escape into the return pipe.

It will, of course, be understood that any other forms of valves may be employed than those illustrated herein and that automatically actuated valves controlled thermostatically, or in any suitable manner, may be provided for controlling the admission into the heat radiating units and that any suitable type of valve, either manually or automatically operated, may be provided for permitting the heating fluid to escape into the return riser. It will also be understood that the radiator may be employed upon any type of heating system to which it may be adapted, such as, steam, vapor or hot water systems.

A further feature of the invention consists in providing a radiator section which may be employed either in a two pipe system as disclosed, or in a single pipe system. Where a single pipe system is employed the construction illustrated in Fig. 2 may be used by merely inverting the radiator section thereby admitting steam through the valve, which is at the lower end of the heating section, and permitting the condensate to run out through the same valve.

In all of these constructions the conduit

desirably is straight and extends longitudinally of the heat radiating section so that it may be connected directly into the riser of the heating system in such a manner as to form a continuous part thereof.

The radiator sections above described, comprising the heat radiating section and the conduit, may be readily cast from iron, or other suitable metal, as an integral unit and obviously may be made of any desired form corresponding to the standard radiator sections with which it is to be associated, or special constructions may if desired be made.

It will, therefore, be understood that the present embodiment of the invention is of an illustrative character and is not restrictive and that various changes in design, construction and arrangement of parts may be made within the spirit and scope of the following claims.

Having thus described the invention, what is claimed as new, and desired to be secured by Letters Patent, is:

1. A radiator comprising a series of vertical loop sections communicating horizontally at the top and bottom through nipple connections, one section of which radiator comprises a loop member having at its respective ends coupling means for connecting the same to a vertical riser for the heating fluid, to form a continuous part of said riser and the wall of which is provided with a valve-controlled port communicating with the other loop member of said section.

2. A radiator having a series of assembled communicating vertical heat radiating sections comprising an intake section having a conduit integral therewith and extending longitudinally thereof and provided at its respective ends with coupling means for connecting said conduit into a vertical supply riser for the heating fluid and thereby to

form a continuous part of said supply riser, a valve-controlled port leading from said riser to said intake section, and an outlet radiator section having a delivery conduit extending longitudinally thereof and provided at its respective ends with coupling means for connecting said conduit to the return riser for the heating fluid to form a continuous part thereof.

3. A radiator having a series of assembled communicating vertical heat radiating sections comprising an intake section having a conduit integral therewith and extending longitudinally thereof and provided at its respective ends with coupling means for connecting said conduit directly into a vertical supply riser for the heating fluid and thereby to form a continuous part of said supply riser, a valve-controlled port leading from said conduit to said intake section, an outlet radiator section having a delivery conduit extending longitudinally thereof provided at its respective ends with coupling means for connecting said conduit directly into the return riser for the heating fluid to form a continuous part thereof and a port having a thermostatically controlled valve leading from said outlet section to said return riser.

4. A radiator section adaptable for assemblage with standard sections of a vertical loop sectional radiator, the rear loop member of said section having at its respective ends coupling means for connecting the same to a vertical riser for the heating fluid, to form a continuous part of said riser and the wall of which is provided with a valve-controlled port communicating with the other loop member of said section.

In testimony whereof, I have signed my name to this specification.

FRANK A. MERRILL.
